DRIVING DEVICE FOR PIPES

Filed Feb. 20, 1928

UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

DRIVING DEVICE FOR PIPES

Application filed February 20, 1928. Serial No. 255,705.

This invention relates to rock drills, but more particularly to a driving device adapted to be actuated by a rock drill for driving a hollow member, such as a pipe, into the soft strata overlying the rock intended to be drilled.

The objects of the invention are to eliminate the necessity of removing the soft material or overburden overlying the rock intended to be drilled and to prevent the entrance of loose material into the drill hole prior to the charging thereof.

Other objects will be in part obvious and in part pointed out hereinafter.

15 In the drawings accompanying the following description,

Figure 1 is an elevation of a drill wagon and a rock drill illustrating a practical application of the invention,

20 Figure 2 is a transverse view taken through Figure 1 on the line 2—2 looking in the direction indicated by the arrows,

Figure 3 is a sectional view taken through Figure 2 on the line 3—3 looking in the direction indicated by the arrows,

25 Figure 4 is a transverse view taken through Figure 1 on the line 4—4, and

Figure 5 is an enlarged elevation of the guide plate illustrating the manner in which 30 they may be clamped to the guide frame.

Referring more particularly to the drawings, A designates a drill wagon having a frame B comprising a pair of vertical guide members C on which is slidably mounted a 35 carriage D supporting a rock drill E.

At the upper end of the frame B is a shaft F on which are mounted a pair of sheaves G and H overrun by cables J and K respectively. One end of the cable J is secured to 40 the frame D and the other end may be wound on a motor hoist L mounted on the drill wagon A for raising and lowering the drill E.

In accordance with the present invention, 45 means are provided for driving a drill pipe O through the ground P overlying rock Q intended to be drilled. These means comprise a drive head R interposed between the front end of the drill E and the rearward end of 50 the pipe O. The drive head R preferably has

a recess S to receive the end of the pipe and a bore T coaxial with the recess S to enable the drill steel T' to extend therethrough. Means such as a set screw U threaded into the drive head R may be used for clamping 55 the pipe O to the drive head.

In order to maintain the drive head R in operative position with respect to the drill E said drive head is provided on opposite sides with guideways V to receive slidably the 60 guide members C of the frame B. On one side of the drive head R is secured an eye-bolt W to which one end of the cable K may be attached. The other end of the cable K may be wound on a motor hoist X disposed on the 65 drill wagon A for raising and lowering the drive head R.

Means are provided for guiding the pipe O near the point at which said pipe enters the ground P. These means comprise a pair of 70 plates Y and Z having curved portions b and c which cooperate to serve as a guide for the pipe O. To the end that the plates Y and Z may be readily clamped to the guide members C the plate Z is provided with a pair 75 of apertures d through which extend tongues e carried by the plate Y. The tongues e preferably have oblong apertures f for the reception of wedges j which, when driven into position in the apertures f, will clamp 80 the plates Y and Z firmly against the guide members C and maintain said plates in that position unaffected by the vibration set up in the drilling apparatus.

Any suitable means such as chains k may 85 be attached at one end to the wedges j and at their other ends to the plate Z to connect the wedges j to the plate.

In the construction shown the pipe O consists of two pieces, a body portion o and 90 what may be termed a bit p. The bit p is secured to the body portion o by means of a threaded connection q and has an inner tapered surface r at its front end to form a knife edge s for the purpose of directing the 95 loose soil into the pipe O through which it may pass into the drive head R and thence through lateral holes t to the surface of the ground.

100 Preferably the cutting bit of the drill steel

T' extends slightly in advance of the bit *p* of the pipe O. In this way the material through which the pipe passes is gradually displaced and only a small portion of material will therefore have to be removed by the knife edge *s* of the bit *p*.

5 The operation of the device is as follows: After the drive head R has been disposed on the guide members C and raised to a position so that it abuts the front end of the rock drill E the pipe O with the drill steel T' therein may be placed in operative position so that the upper end of the pipe O will extend into the recess S wherein it may be clamped by the set screw U. After these 10 parts have been assembled in the manner described the clamp plates Y and Z are clamped to the front end of the guide member C by means of the wedges *j*. The drilling apparatus may then be set in operation and the pipe O will be driven through the ground P until the bit *p* rests on the rock Q. The set screw U may be unscrewed and the drilling apparatus together with the drive head R 15 may be raised by means of the motor hoists L and X. After the drill hole is completed the clamp members Y and Z are disconnected from the frame B the drilling apparatus may be removed to another site. The pipe O 20 may remain in the strata P until the hole has 25 been charged.

I claim:

In a driving device for driving a pipe through soft strata overlying the rock intended to be drilled, the combination of a 20 rock drilling machine having its drill steel passing through the pipe being driven and a guide frame for the drilling machine, a drive head between the rock drill and the pipe and against which the body of the drilling machine is adapted to bear for driving the pipe, guideways in the drive head to slidably receive the frame for guiding the drive head, said drive head having a recess to receive the end of a pipe intended to be 25 driven, and means clamped to the frame for guiding the pipe near the point of entrance of said pipe into the soft strata.

In testimony whereof I have signed this 30 specification.

CHARLES C. HANSEN.
